Primary Examiner—A. Hugo Word*Assistant Examiner*—Eric Watterson*Attorney, Agent, or Firm*—Quarles & Brady**[57] CLAIM**

The ornamental design for a tub for bathing, as shown and described.

DESCRIPTION

FIG. 1 is a perspective view taken from the top, front and right side of a tub for bathing embodying my new design;

FIG. 2 is a top plan view thereof;

FIG. 3 is a left side elevational view thereof;

FIG. 4 is a right side elevational view thereof;

FIG. 5 is a front elevational view thereof;

FIG. 6 is a cross-sectional view taken on line 6—6 of FIG. 2;

FIG. 7 is a cross-sectional view taken on line 7—7 of FIG. 2;

FIG. 8 is a rear elevational view of the embodiment of FIG. 1;

FIG. 9 is a perspective view taken from the top, front and right side of a second embodiment of my new design, the right side, left side and cross-sectional views being the same as that shown for embodiment 1;

FIG. 10 is a top plan view of the embodiment of FIG. 9;

FIG. 11 is a front elevational view thereof;

FIG. 12 is a cross-sectional view taken on line 12—12 of FIG. 10;

FIG. 13 is a rear elevational view of the embodiment of FIG. 9;

FIG. 14 is a perspective view taken from the top, front and right side of a third embodiment of my new design, with all other sides being a mirror image to that shown for embodiment 1; and,

FIG. 15 is a perspective view taken from the top, front and right side of a fourth embodiment of my new design, with all other sides being a mirror image to that shown for embodiment 2.

UNITED STATES PATENT AND TRADEMARK OFFICE
CERTIFICATE OF CORRECTION

PATENT NO. : Des. 353,656

DATED : December 20, 1994

INVENTOR(S) : Iain M. Smith

It is certified that error appears in the above-identified patent and that said Letters Patent is hereby corrected as shown below:

ON THE TITLE PAGE:

The description of Fig. 9 should be as follows:

--Fig. 9 is a perspective view taken from the top, front and right side of a second embodiment of my new design, the right side, left side and the cross-sectional view of Fig. 7 being the same as that shown for embodiment 1;--

Signed and Sealed this
Eleventh Day of July, 1995
